APPARATUS FOR SEPARATING MIXED MATERIALS HAVING DIFFERENT ELECTRICAL CONDUCTIVITIES

Kenelm Charles Appleyard, Birtley, and Stanley Dallas Pollitt, Newcastle-upon-Tyne, England, assignors of one-third to The Birtley Company Limited, Birtley, England

Application April 22, 1937, Serial No. 138,454
In Great Britain April 18, 1936

4 Claims. (Cl. 209—81)

This invention relates to the separation, into classes according to their electrical properties, of mixed materials, such as coal with shale or other refuse and more particularly to automatically resetting devices for making temporary electrical contact with individual pieces of the material whilst the latter are moved past the contact devices.

Coal separating machines utilizing such devices are described in British patent specification No. 421,401 wherein pieces of coal and stone are caused to pass one or more sets of resilient contact making devices in the form of brushes, combs or fingers operating sometimes in conjunction with a conveyor belt or the like of conductive material.

In such cases the free length of the wires constituting the brush must be kept as small as possible in order to reduce as far as possible the overall size of the apparatus.

Reduction of the length of wire projecting from the rigid stock entails the risk that a large piece of material passing between them may bend them to such an extent as to cause a permanent set in them.

Pieces of material may also strike the wires close to the root or anchoring point and thus badly damage them.

The main object of the invention is to overcome this disadvantage and other objects and advantages will appear in the following description. The invention will be pointed out in the accompanying claims.

The invention will now be described by way of example with reference to the accompanying drawings, in which:—

Figure 1 is a general view in elevation of a conveyor belt and two sets of contact members.

Figure 2 is an end elevation of Figure 1.

Figure 3 is an end elevation of Figure 1 with the foremost set of contact members removed.

Figure 4 is a plan view of the foremost contact members in Figure 1 drawn to a larger scale to show the resilient springing of the fingers.

Figure 5 is a general elevational view similar to Figure 1 but showing a conveyor belt which is rendered conductive only from face to face by a plurality of inset conductors.

Figures 6, 7 and 8 are a plan and sectional views respectively of the conveyor belt of Figure 5 to an enlarged scale.

Figure 9 is a modified form of resilient mounting for the contact members.

Figures 10 and 11 are elevational views at right angles of another modified form of contact mem-

ber employing a plate like member and a hinged and helical spring controlled resilient mounting.

According to Figures 1 to 4 of the drawings, pieces 1 of the material to be tested are fed in single pieces at spaced intervals to an electrically conductive conveyor belt 2 upon which they are conveyed past two contact devices 3 and 4 respectively and delivered to a chute 5 and thence to a selecting device not shown, but operated in accordance with the effect upon an electrical circuit associated with the contact devices 3 and 4 of each piece of material as it passes them.

The contact device 3 comprises a brush like member having a stock portion 6 and a set of flexible conductive wires 7, and the above mentioned electrical circuit is completed when a piece of material passes beneath the member 3 and connects, in a more or less conductive manner, according to its electrical resistance the member 3 with the conductive belt 2 as shown in Figure 3.

The contact device 4 comprises a pair of members similar to the member 3, but arranged as shown in Figures 1 and 2 in such a way that the flexible wires 7 are disposed in a vertical plane but in a horizontal direction towards one another. These brushes 4 are hereinafter referred to as the horizontal brushes.

The two sets of wires 7 approach one another at their free ends but do not touch and the pieces of material are conveyed on the belt 2 so as to bridge the gap 8 between them.

Each of the elements 7 making up a contact brush 3 or 4 is connected, as shown in Figure 4, to the common root or stock 6 by way of a resilient spiral part 9 which is protected against damage from the travelling pieces of material 1 by being shielded by the stock of the brush. The material is caused to pass from right to left in Figures 1 and 4. Should a piece of material be so wide as to reach close to the stock or be travelling in such a direction as to strike against the stock, then the spiral part 9 unwinds and takes the bending stress off the root of the element 7.

In the form of the invention shown in Figure 5 the elements of the brushes 4 are flexible in planes which include the vertical with the result that the lower elements of these brushes may touch the belt, and effect undesirable results if the belt is completely conductive.

In order to avoid these results and to allow of setting the horizontal brushes 4 close to the belt, in this form of the invention the conveyor belt 20 is made of rubber, vulcanized cloth or

other suitably strong electrically insulating material. Set into the belt are small hardened steel staples, rivets or studs of conductive material 21, each electrically insulated from the other by the material of the belt, and resulting in a series of closely spaced contacts each making an electrical circuit through the belt, and each electrically insulated from the other. This construction is shown in detail in Figures 6, 7 and 8.

The drum over which the belt passes is made or faced with non-conductive material such as rubber so as not to short-circuit all the contact points 21 of the belt as it passes over the drum. Underneath the belt 20, directly underneath the vertical brush 3, a series of brushes 22 are fixed so as to make contact over a considerable area of the belt. These brushes are so arranged that they make contact with the conductive staples 21 on the underside of the belt, sufficiently far on either side of the vertical brush as to include the length of the largest piece of material passing through the apparatus.

A circuit is thus completed vertically through any piece of material via the vertical brush, the piece of material, the conductive studs and the bottom brush. By the time a point of the belt 20 reaches the horizontal brushes 4 which succeed the vertical one 3, it has left the zone of contact of the bottom brushes 22. It is therefore possible to set the horizontal brushes 4 down as close to the belt 20 as is desired because the studs immediately below them are insulated from earth and contact between the horizontal brush and the belt is of no consequence.

Figure 9 shows a zigzag or serpentine attachment 9 which may be used instead of the spiral form of resilient attachment shown in Figure 4.

In the form of the invention shown in Figures 10 and 11 the contacting member corresponding to 3 above comprises a single deflectable element 7 in the form of a thin sheet of steel, aluminium or other suitable metal, hinged to the stock part 6 on a horizontal axis 10 by pivots 11 so that it can swing forward and return under the action of the tension spring 12 on the tail piece 13.

The member 7 in this case may be formed as shown in Figures 10 and 11 of a replaceable wearing part 14, a permanent part 15 and the tail piece 13.

In a further modification the parts 7 in Figures 4 and 9 may be regarded as end views of a single sheet of conductive material provided with resilient means shown in Figures 4 and 9.

We claim:

1. In apparatus for the separation of mixed

materials according to the electrical conductivities of the pieces of material, a conveyor belt device having electrically conductive elements spaced therealong and extending from face to face through the thickness of the belt and upon which the pieces of material are adapted to be conveyed singly in series, a downwardly directed relatively fixed but resilient contact member, a pair of laterally disposed contact members spaced apart and arranged along the conveyor in a spaced relation with respect to the downwardly directed contact member, and means for making continuous electrical contact with an area of the underside of the conveyor belt device immediately beneath said downwardly directed contact member.

2. Apparatus as claimed in claim 1, wherein the downwardly directed and the laterally disposed contact members each comprise a stock portion and an electrically conductive member projecting beyond the stock portion and lying in the path of the pieces of material, and resilient electrically conductive means connecting said conductive member and said stock portion positioned behind said stock portion so as to be shielded thereby from passing pieces of material.

3. Apparatus as claimed in claim 1 wherein the downwardly directed and the laterally disposed contact members each comprise a stock portion and an electrically conductive member projecting beyond the stock portion and lying in the path of the pieces of material, and resilient electrically conductive means connecting said conductive member and said stock portion positioned behind said stock portion so as to be shielded thereby from passing pieces of material, and said resilient electrically conductive means being of convoluted form and integral with said projecting member.

4. Apparatus as claimed in claim 1 wherein the downwardly directed and the laterally disposed contact members each comprise a stock portion and an electrically conductive member projecting beyond the stock portion and lying in the path of the pieces of material, resilient electrically conductive means connecting said conductive member and said stock portion positioned behind said stock portion so as to be shielded thereby from passing pieces of material, said resilient electrically conductive means comprising a convoluted wire integral with the projecting member, and the convolutions of said wire being arranged in a single plane.
